UNITED STATES PATENT OFFICE.

GILBERT PARK, OF SPENCER, MASSACHUSETTS, ASSIGNOR OF ONE-HALF TO
JOHN G. AVERY, OF SAME PLACE.

LET-OFF MECHANISM FOR LOOMS.

SPECIFICATION forming part of Letters Patent No. 431,707, dated July 8, 1890.

Application filed September 10, 1889. Serial No. 323,549. (No model.)

To all whom it may concern:

Be it known that I, GILBERT PARK, a citizen of the United States, and a resident of Spencer, in the State of Massachusetts, have 5 invented a new and useful Improvement in Let-Off Mechanism for Looms, of which the following is a specification.

This invention consists of certain novel combinations of parts, hereinafter set forth 10 and claimed, designed for application to the different makes of power-looms now commonly used and to looms constructed on the same general principle, in which the warp-beam is or may be positively turned a greater 15 or less distance to let off the warp for one pick at each half-turn of the main shaft by means of a cam on the latter, through the medium of suitable pawl-and-ratchet converting mechanism and worm-gearing.

20 The objects of the present invention are, first, to automatically and positively increase the movement of the warp-beam in proper proportion as its diameter decreases by means of a screw-actuated back-stop and without 25 the contact of any part of the mechanism with the warp itself; secondly, to provide for regulating the number of picks for different sizes of yarn with such screw mechanism; thirdly, to facilitate resetting the mechanism 30 when a fresh warp-beam is put in the loom; fourthly, to prevent overmovements of heavy warp-beams by inertia; and, fifthly, to provide for operating in the most direct manner the positively-acting "automatic grip" or gripping device, by which such overmovements 35 are prevented.

Two sheets of drawings accompany this specification as part thereof.

Figure 1 of the drawings represents a vertical cross-section through the frame warp-beam spindle and main shaft of a loom, showing its let-off mechanism in elevation. Fig. 2 represents a sectional view of the parts of the latter at and below the plane indicated 45 by the line 2 2, Fig. 1. Fig. 3 is a fragmentary perspective view showing the automatic grip and a supplemental device for preventing overmovements of the warp-beam. Fig. 4 is a fragmentary perspective view showing 50 the screw-actuated back-stop and its appur-

tenances. Fig. 5 is a like view showing a modification of the screw mechanism, and Fig. 6 is another like view showing a modification of the automatic grip.

Like letters of reference indicate corresponding parts in the several figures.

For the purposes of this invention the required slow intermittent motion may be imparted to the spindle A of the warp-beam by the rotary main shaft B, through the medium 60 of any suitable cam C on the latter, and any approved pawl-and-ratchet or like converting mechanism and any suitable worm-gearing. I prefer an oval cam fast on the shaft and projecting equally on opposite sides thereof, 65 as shown in Figs. 1 and 4, and the converting mechanism and worm-gearing represented in Figs. 1 and 2. Such converting mechanism comprises a lever D, which works on a pivot E, supported by the end frame of the 70 loom adjacent to which the cam C is located. Said lever is connected by a link F with an oscillating dog-holder G, whose dogs H mesh with a crown ratchet-wheel I, fast on a vertical ratchet-shaft J, and the latter carries the 75 customary screw or worm K in mesh, when in operation, with a worm-wheel L, fast on the warp-beam spindle A. The cam C is preferably set on the shaft B so that it lets off when the lay is going back. Thus when the lay 80 strikes the cloth the warp is held taut and the filling goes in better. The lower end of the lever D is composed of several parts united by screws passing through longitudinal slots, as shown in Figs. 1, 2, and 4, so as 85 to provide for varying the distance between its pivot E, which is conveniently fixed, and its terminal contact-piece which is engaged by the cam. Finer adjustments to determine the number of picks with greater nicety are 90 provided for at the top of the lever. The dogs H are preferably four in number, and each of the last three is an eighth of an inch shorter than the preceding dog, so that one will always bite one of the crown-teeth of 95 the ratchet-wheel. The number of dogs may be increased for finer work, and the variation in their length reduced to one-sixteenth of an inch. The dogs are held down to their work by springs. A dog-lifter V, in the form 100

of a slotted disk with a radial arm over each dog, is held down upon the dog-carrier G, and its independent motion is limited by screws (not herein shown) passing through its slots.

5 (Not herein shown.) The dogs have inclined rear ends to coact with the said radial arms of the dog-lifter, and by turning the latter independently of the dog-carrier the dogs are simultaneously lifted clear of the ratchet-teeth, so as to free the ratchet-shaft when a fresh warp-beam is being attached, or in case of pick-outs. A hand-rod W provides for turning the dog-lifter from the front of the loom in case of pick-outs; and, in addition to 10 a hand-wheel X, fast on the ratchet-shaft at its upper end, it is provided with a fast gear-wheel Y, meshed by a pinion Y^2 , which is carried by the rear end of a horizontal shaft Z, the front end of which is furnished with a 15 hand-wheel X^2 to provide for readily turning the ratchet-shaft from in front of the loom in case of pick-outs.

The above converting mechanism and worm-gearing are more fully described and are 20 shown more in detail and referred to for the most part with like reference-letters in the specification and drawings forming part of a previous application for patent filed by me July 23, 1889, Serial No. 318,373, in favor of 25 which all patentable features thereof are hereby disclaimed. To gradually increase the action of said converting mechanism and worm-gearing in due proportion to the decreasing diameter of the warp-beam M, I propose 30 vide the warp-beam spindle A with a worm N, rigidly fastened thereon, and transmit motion therefrom through the medium of a small worm-gear O, a screw P, a nut Q or Q^2 , and preferably a peculiarly-slotted lever R, to 35 a back-stop S, which coacts with a reciprocating or oscillating part of said converting mechanism, and preferably with a shoulder of the yoke portion which carries the contact-piece of said lever D immediately adjacent 40 to the cam C, so as to limit the retraction and consequently the succeeding throw of said part, and thus to limit each effective movement of the dogs H and the consequent fractional turn of the ratchet-wheel I, shaft J, and 45 worm K and that of the worm-wheel L, spindle A, and warp-beam M in a direct and positive manner without touching the warp itself. Said worm-gear O is fast on the screw P between a pair of bearings at the extremity of 50 a bracket T, which is attached to the adjacent end frame of the loom by a pivotal stem p, Fig. 4, in line with the horizontal diameter of the gear, and so located that the worm N meshes properly therewith when the spindle 55 A drops into its open bearings, as indicated in Figs. 1 and 4. The screw P and said worm-gearing, through which it is actuated, are proportioned to the warp-beams and warp which are to be used in the loom. With a warp-beam carrying six hundred turns of warp, I 60 use a worm of four and a half threads to the inch and a forty-tooth gear on the screw, the

latter being cut ten threads to the inch, and the nut Q or Q^2 , which is fitted to said screw, is consequently moved one and a half inches 70 during the emptying of a beam. The nut Q or Q^2 has a pivotal stem q, which passes through a longitudinal slot a in said lever R, and by fastening the nut higher or lower in said slot a the graduating mechanism is adjusted for different sizes of yarn. With coarser yarn the nut is raised. With finer 75 yarn it is lowered.

The nut Q (shown in Figs. 1, 2, and 4) is divided diametrically and provided with a 80 clamp-screw c, Fig. 4, so that it may be released from the screw P and reclamped thereon at the starting-point to facilitate resetting the back-stop S when a new warp-beam is put in the loom. A one-part nut may be used instead, as shown at Q^2 in Fig. 5 and be run back by turning the gear O by hand after the empty warp-beam is removed from the loom.

The lever R is conveniently supported by a fixed pivot E² at its upper end, the same being attached to the adjacent end frame of the loom, and this lever carries the back-stop S at its opposite end, being provided with a slot b, within which the back-stop is adjustable toward or away from said surface s, with 95 which it coacts, so that the lever may hang as nearly vertical as is practicable with the back-stop at the proper distance from said coacting surface at the beginning of the operation.

The parts of the converting mechanism are shown as they appear at the end of an effective stroke, and the said nut Q, lever R, and back-stop S of the graduating mechanism are shown as they appear when the warp-beam is 105 full, and the dotted lines in Fig. 1 represent the movement of these parts by the warp-beam spindle A through the medium of the worm N, worm-wheel O, and screw P.

To prevent overmovements of heavy warp-beams by inertia, an automatic grip is preferably added to the said converting mechanism, as follows, (see Figs. 1, 3, and 6.) A pair of short levers U' U² are hinged together at one end and form, adjacent to their hinge h, 115 Figs. 3 and 6, concave jaws, which are provided with linings j, Figs. 3 and 6, of leather or the like to coact with the ratchet-shaft J, which is embraced by said jaws at a convenient point. The other end of the jaw-lever U' is attached by a vertical pivot p' to a bracket U³, which is affixed to said adjacent end frame of the loom, and the corresponding end of the jaw-lever U² carries a contact-piece U⁴ or U⁵, the free end of which coacts with the opposing edge of the lever D of the converting mechanism as the latter approaches the invariable limit of its effective movements. To vary the "grip" of the jaws upon the shaft when so closed, the contact-piece U⁴ or U⁵ is adjusted endwise, which adjustment is provided for by a longitudinal slot d, Figs. 3 and 6, formed in the contact-piece to receive an attaching-screw e. Said automatic grip may be located

above the pivot E of said lever D, as shown in Figs. 1 and 3, or below said pivot and below the worm I, as shown in Fig. 6. In the latter arrangement the jaw-levers U' U² are 5 reversed. Said jaw-lever U' is pivoted to the lower bearing J' of the shaft J, and the contact-piece U³ is adapted, by a rebent outer end f, to coact with the far or front edge of the lever D.

10 As a supplemental or alternative device for preventing overmovements of the warp-beam, I employ a spiral drag-spring V', Figs. 1 and 3, surrounding the ratchet-shaft J. The same is coiled in a direction opposite that of the ordinary rotation of the shaft, and is conveniently compressed, more or less, as required, between the upper bearing J² of said shaft and an opposing collar V², which is adjustably fastened on the shaft by a screw g.

15 20 Details which have not been specified may be of any approved description, and other like modifications will suggest themselves to those skilled in the art.

Having thus described the said let-off for 25 looms, I claim as my invention and desire to patent under this specification—

1. The combination, with the warp-beam, the warp-beam spindle, and a reciprocating part and connections which turn said beam 30 and spindle, of a worm carried by said spindle, a worm-gear driven by said worm, a screw and nut transmitting motion from said gear, and a movable back-stop which coacts with said reciprocating part and is retracted 35 through the medium of said screw and nut at each movement of the warp-beam, said worm, worm-gear, screw, and nut being proportioned to the number of turns of warp on the warp-beam, so that the escape of a given 40 length of warp is accompanied by a proportionate retraction of the back-stop, substantially as hereinbefore specified.

2. The combination, with the warp-beam

spindle, worm-gearing transmitting motion therefrom, a screw turned by said gearing, 45 and a nut fitted to said screw, of a lever having a pivot at one end, provided at its other end with a back-stop, and provided intermediate with means for attaching said nut thereto and adjusting the same toward or away 50 from said pivot, substantially as hereinbefore specified.

3. In combination with the warp-beam spindle, worm-gearing transmitting motion therefrom, a screw turned by said gearing, and a 55 back-stop actuated by said screw, an interposed nut fitted to said screw, divided diametrically and provided with a clamp-screw, substantially as hereinbefore specified.

4. The combination of a rotary let-off cam, 60 a pawl-and-ratchet converting mechanism actuated by said cam, a shaft actuated by said mechanism, worm-gearing transmitting motion from said shaft, a warp-beam spindle intermittently turned by said gearing, a gripping device applied to said shaft, and transmitting devices, whereby said gripping device is periodically tightened to prevent overmovements of the warp-beam, substantially 65 as hereinbefore specified.

5. The combination, with the ratchet-shaft and a reciprocating part and connections transmitting motion thereto, of a pair of jaw-levers hinged together at one end and having concave portions which embrace said shaft, 75 a fixed pivotal support at the outer end of one of the jaw-levers, and a contact-piece carried by the outer end of the other jaw-lever and coacting with said reciprocating part at the end of its effective movements, substantially 80 as hereinbefore specified.

70 GILBERT PARK.
